UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

HINGE FOR VEHICLE-DOORS.

1,164,857.

Specification of Letters Patent. Patented Dec. 21, 1915.

Application filed July 23, 1914. Serial No. 852,623.

To all whom it may concern:

Be it known that I, STUART W. PARSONS, a citizen of the United States, and a resident of New Britain, in the county of Hartford, and State of Connecticut, have invented certain new and useful Improvements in Hinges for Vehicle-Doors, of which the following is a specification.

This invention is particularly adapted for 10 use as a hinge support for the doors of vehicles such as automobiles, the object of the invention being to produce a device of the character described having features of novelty and advantage.

15 In the drawings Figure 1 is a view of a hinge made in accordance with my invention showing its manner of application, the hinge being illustrated as in the open position of the door. Fig. 2 is an end view of the hinge 20 itself, showing the two leaves closed. Fig. 3 is a side view of a stationary leaf, the movable leaf being shown open. Fig. 4 is the front view of the stationary leaf, with the movable leaf shown open. Fig. 5 is a separation view of the locking device.

25 Referring to the drawings, *a* denotes the vehicle body in which is mounted the stationary leaf 1, and *b* the door which is secured to the movable leaf 10. The stationary leaf 1 is provided with a pocket 2. The movable leaf 10 is provided with an arched arm 11 which fits and moves in the pocket 2, the end of the arm being apertured as at 12 to receive the pintle 3 which is supported 30 in the pocket 2 and preferably mounted in an extension 4 of one wall thereof. The arched arm 11 as shown is of double thickness, formed by properly shaping and bending two separate pieces of metal, placing the 35 arm members face to face and securing them together as by welding.

40 The shape of the arched arm 11 and its point of pivotal connection with the extension 4 of a wall of the pocket 2 are such that 45 when the parts of the hinge are in closed position the face plates lie closely adjacent to one another and in substantially parallel relation, and when open the face plates are at substantially right angles to one another, 50 these two positions being clearly shown in Figs. 1 and 2. In order to limit the extent of opening of the hinge members there is formed on one edge of the face plate of the stationary leaf 1, stops 5 which engage the 55 inner edge of the arched arm 11, as clearly

shown in Figs. 1, 3 and 4, to limit the extent of opening movement of the movable leaf 10. It is preferable to lap one of these projections over the other and weld them at the point indicated at *X* in Fig. 3, in order to 60 add stiffness and rigidity to the structure.

While the ends of the pintle may be supported in both walls of the pocket, thus 65 permanently uniting the hinge members, I prefer to utilize the construction here shown and described in order that the two parts of the hinge may be separated by lifting the movable leaf so that its arched arm will be 70 disengaged from the pintle. In order to provide for this separation of the hinge 75 parts it is necessary to slot the face of the stationary leaf 1, as indicated at 6, in order to give a space within which to move the end of the arched arm 11; and in order to guard against the accidental disengagement 80 of the arm from the pintle there is provided a stop 15 which fills in this slot 6 after the hinge members are assembled together, with its end lying against the side of the arched arm 11, as clearly seen in Fig. 4, this stop 85 having an apertured and countersunk head which registers with one of the attaching screw holes and is held in position by one of the attaching screws.

Figs. 3 and 4 indicate how a pair of these 90 hinges may be made together, one pair at each end of a strip *y*, but it is obvious that my invention is not concerned with the manner in which pairs of hinges may be connected together.

I claim as my invention:

1. In an article of the character described, a stationary leaf member comprising a base bent at an intermediate point to form a U-shaped pocket, a movable leaf member comprising a base and an arched arm arranged at right angles thereto and fitting and movable within said pocket, a pin connecting said arm and pocket to pivotally unite the two leaves, and a projection at the edge of the base of the stationary leaf extending across the mouth of the U-shaped pocket and forming a stop cooperating with the arched arm on the movable member.

2. In an article of the character described, a stationary member of wrought metal comprising terminal face plate portions and a rearwardly extending pocket formed by bending the metal to U shape at an intermediate point, a movable member comprising

ing a base and an arched arm movable in said pocket and pivotally connected therewith, and projections from an edge of said face plate at opposite sides of said pocket, 5 partially bridging the mouth of the pocket and adapted to coöperate with said movable member to limit its swing in one direction.

3. In an article of the character described, a stationary leaf member comprising a base 10 bent at an intermediate point to form a U-shaped pocket, a movable leaf member comprising a base and an arched arm arranged

at right angles thereto and fitting and movable within said pocket, a pin connecting said arm and pocket to pivotally unite the 15 two leaves, and oppositely extending overlapping projections at the edge of the base of the stationary leaf permanently secured together and forming a stop coöoperating with the arched arm on the movable member. 20

STUART W. PARSONS.
